UNITED STATES PATENT OFFICE.

FRANK W. CALVERT, OF SWARTHMORE, PENNSYLVANIA, ASSIGNOR TO SCOTT PAPER COMPANY, A CORPORATION OF PENNSYLVANIA.

DISPENSING CABINET.

1,403,007.

Specification of Letters Patent. Patented Jan. 10, 1922.

Application filed August 4, 1917. Serial No. 184,392.

To all whom it may concern:

Be it known that I, FRANK W. CALVERT, a citizen of the United States, and resident of Swarthmore, county of Delaware, and State 5 of Pennsylvania, have invented an Improvement in Dispensing Cabinets, of which the following is a specification.

The object of my invention is to provide an improved construction of dispensing cabinet 10 for toilet papers, which shall be more efficient and durable than constructions of similar devices heretofore in use.

My invention comprehends certain features of construction, more particularly relating 15 to the spring mechanism for forcing the paper pad forward against the dispensing or discharging roll, whereby it is strongly installed in the casing and shaped to maintain its effective elasticity for the life of 20 the cabinet without breaking. My invention further embodies, in a cabinet employing a dispensing roll provided with a roughened surface for securing an efficient frictional contact with the paper and a spring actuated 25 pressure plate adapted to force the paper pad or tablet toward the dispensing roll, of means for limiting the approach of the pressure plate toward the roll whereby the roughened surface thereof is prevented from 30 becoming worn off by undesirable direct contact with the pressure plate.

My invention also consists of details of construction which, together with the features above stated, will be better understood 35 by reference to the accompanying drawings, in which:—

Fig. 1 is a front sectional view on line $x-x$ of Fig. 2 of a cabinet embodying my improvements, the front cover portion being 40 removed to show the interior; Fig. 2 is a vertical sectional view of the same taken on line $y-y$ of Fig. 1; Fig. 3 is a cross section of a portion of the same on line $z-z$ of Fig. 1; Fig. 4 is an elevation showing the construction for holding the spring of the 45 presser plate in position; and Fig. 5 is a perspective view of one of the retaining plates for holding the aforesaid spring.

The case is provided with sides 2, back 3 and bottom 4, and is adapted to be closed by a front cover 5, extending over the top and hinged to the back at 6. The lower part of the cover 5 is provided with latch hooks 21 which engage locking arms 20, said locking 55 arms being secured to a rock shaft 20^a and

spring pressed into locking engagement by coil springs 22. Any other suitable locking means may be employed for holding the cover closed, such devices being well known in the art. The bottom 4 of the case is provided with the inclined floor plate 18 having the downwardly directed inclined front portion 19 to guide the paper sheet through the discharge orifice 7. This discharge orifice is formed between the end of plate 19 and the bottom plate 4 on the one part and the lid 5 on the other, so that when the hinged cover is raised, the discharge orifice is completely open in the front and permits easy cleaning in case of clogging. The cover 5 is provided near its lower part with a roller 8 having roughened surfaces at 9, preferably formed of abrading material such as emery or corundum cemented upon the roller, the latter usually being of wood and secured upon a metal shaft 10. This shaft 10 is journaled in suitable bearings on the cover so as to be carried by and moved with it. It is further provided with the usual ratchet wheel and pawl device at 12 for preventing 75 backward rotation, and with a hand wheel 11 upon the outside of the cabinet by which to rotate the shaft 10 and its roller 8. This construction of the roller and means for operating it may be of the well known construction and will need no further explanation.

Hinged at or adjacent to the hinge point 6 of the cover is the presser plate 13, the lower part 16 thereof being bent forward 90 slightly and adapted to approach the roller 8 but held against contacting with it by the two side arms 23 which rest against the cover plate 5, when the plate 13 is in its most forward position. The function of 95 this plate 13 is to support and force the paper pad or tablet 15 against the roughened surfaces 9 of the roller 8, said pressure for performing this function being provided by the spring 24. If it were not for the arms 100 23 acting as limit stops for the plate 13, the spring 24 would force the lower part 16 of the plate against the abrading surface 9 of the roller, which would not only injure the plate, but where the roughened surface 9 is 105 cemented to the roller 8, said roughened surface material would be objectionably removed to the destruction of the efficiency of the roller as a discharging device. The arms 23 also act as side guides for the paper pack- 110

age 15 to insure its being positioned properly to cooperate with the dispensing roller 9.

The spring 24 is of a construction which provides great elasticity and strength, is 5 easily secured in position in the case, and the possibility of its breaking under strain is entirely overcome. As shown, this spring is bow-shaped and has its lower ends spirally coiled as at 24^a, to provide great elasticity, 10 each of said spirally coiled parts having their wire portions in the same plane so that a minimum space is required therefore in the case. This is important, as it permits the large coils to extend up on each side of the 15 paper tablet 15 and pressure plate 13 without objectionable width being necessary to the case. The coil 24^a has its inner end 25 bent upward and received in a slot formed by two flanges 28 struck up from a retaining 20 plate 26 (Figs. 4 and 5), said retaining plate having on two of its edges, front and bottom, flanges 30 and near its rear a perforated hub-shaped part 29 between which and the back 3 of the case the coil extends (Fig. 4). 25 The plate 26 is bolted against the side plate 2 of the case by a bolt 27, as shown in Fig. 3, and provides a box-shaped chamber in which the coil is encased and its end 25 firmly held. The bottom of the coil 24^a rests upon the 30 bottom flange 30 and is thus held in position vertically and its end 25 retained between the flanges 28, as will be understood by reference to Fig. 4. The two coiled lower ends of the bow spring are formed and secured 35 in the same manner, only it will be manifest that the box-shaped plates 26 are made right and left handed to fit the opposite walls 2 of the case. It will be seen that by this construction the parts are easily and 40 strongly assembled. The upper or bow end of the spring presses upon the plate 13 near its hinged end and consequently a very small movement of the spring produces a considerable movement of the lower end 16 of the 45 plate. Moreover, because of the small movement required of the spring, it may be made of relatively thick wire and hence is not liable to set or break in use.

The paper tablet 15 may be hung upon the 50 plate 13 in any suitable manner, and is so positioned that its lower end just clears the plate 18, and when pressed against the roller 8 the front sheet, when fed downward by the roller, will be guided over the inclined surface 19 and through the aperture 7. The usual method employed for supporting the paper tablet 15 is to provide an upwardly extending tongue 14 from the plate 13 and provide the back of the tablet 15 with a 55 socket part which fits over the tongue, and such construction may be employed, though I do not restrict myself in this particular.

It will now be apparent that I have devised a novel and useful construction which 60 embodies the features of advantage enumer-

ated as desirable, and while I have in the present instance shown and described the preferred embodiment thereof which has been found in practice to give satisfactory and reliable results, it is to be understood 70 that I do not restrict myself to the details, as the same are susceptible of modification in various particulars without departing from the spirit or scope of the invention.

Having now described my invention, what 75 I claim as new and desire to secure by Letters Patent, is:—

1. In a dispensing cabinet, the combination of a case, having a hinged cover part at the front, a dispensing roller journaled on 80 the cover part at its lower portion and having its surface coated with a friction producing substance, a movable pressure plate hinged to the case at its upper and rear portion and having its lower part movable toward the roller and also having two side extensions adapted to contact with the cover for positively arresting the plate when it closely approaches the roller for preventing the roller contacting with the plate and also 85 spaced apart for positioning a package of paper to be dispensed upon the plate and in definite alinement with the roller, and a spring for pressing the plate toward the 90 roller. 95

2. In a dispensing cabinet, the combination of a case, a dispensing roller arranged in the lower portion of the case, a pressure plate connected with the upper part of the case and movable at its lower part toward 100 the roller, a bow spring having its middle upper portion extended back of and pressing upon the pressure plate to force it forward toward the roller and having its two ends respectively extended past each side edge 105 of the pressure plate and coiled spirally into flat coils arranged close to the sides of the case, and connecting means between the inner ends of the spirals and the side walls 110 of the case enclosing the coiled portions of the bow springs and between which the pressure plate may swing.

3. In a dispensing cabinet, the combination of a case, a dispensing roller arranged in the lower portion of the case, a pressure 115 plate connected with the case and movable toward the roller, a bow spring having its middle portion extended back of the pressure plate to force it forward toward the roller and its two ends coiled spirally and 120 arranged close to the sides of the case, and connecting means between the inner ends of the spirals and the side walls of the case comprising box-shaped frames having parallel flange parts for receiving the ends of 125 the spirals and supporting parts for positioning the coils, said frames being secured to the sides of the case.

4. In a dispensing cabinet, the combination of a case, a dispensing roller arranged 130

in the lower portion of the case, a pressure plate connected with the case and movable toward the roller, a bow spring having its middle portion extended back of the pressure plate to force it forward toward the roller and its two ends coiled spirally and arranged close to the sides of the case, and connecting means between the spiral ends of the spring and the sides of the case consisting of stamped metal plates secured to the case and each having flanges on front and bottom 30 and a perforated hub portion of the same lateral depth at the rear and also two parallel flange parts to receive the inner end of the spiral, the coil confined between the front and bottom flanges and back of the 35 case and positioned by the parallel flanges, the flanges and hub portions positioning the plates on the sides of the case, and bolts extending through the perforated hubs and side walls of the case for securing the plates 40 in position.

5. In a dispensing cabinet, the combination of a case, a dispensing roller arranged 20 in the lower portion of the case, a pressure plate connected with the case and movable toward the roller, a bow spring having its middle portion extended back of the pressure plate to force it forward toward the

roller and its two ends coiled spirally and 25 arranged close to the sides of the case, and connecting means between the spiral ends of the spring and the sides of the case consisting of stamped metal plates secured to the case and each having flanges on front and bottom 30 and a perforated hub portion of the same lateral depth at the rear and also two parallel flange parts to receive the inner end of the spiral, the coil confined between the front and bottom flanges and back of the 35 case and positioned by the parallel flanges, the flanges and hub portions positioning the plates on the sides of the case, and bolts extending through the perforated hubs and side walls of the case for securing the plates 40 in position.

In testimony of which invention, I hereunto set my hand.

FRANK W. CALVERT.
